(57) **CLAIM**

The ornamental design for a hair trimmer, as shown and described.

DESCRIPTION

FIG. 1 is a front elevational view of a hair trimmer showing the new design;

FIG. 2 is a back elevational view of the hair trimmer;

FIG. 3 is a top plan view of the hair trimmer;

FIG. 4 is a bottom plan view of the hair trimmer;

FIG. 5 is a right side view of the hair trimmer;

FIG. 6 is a left side view of the hair trimmer;

FIG. 7 is a front perspective view of the hair trimmer; and,

FIG. 8 is a back perspective view of the hair trimmer.

The broken lines shown in the drawings illustrate portions of the hair trimmer and form no part of the claimed design.
